UNITED STATES PATENT OFFICE.

JOSEPH P. DION, OF BIDDEFORD, MAINE.

HEEL-BURNISHER AND EDGE-SETTER.

SPECIFICATION forming part of Letters Patent No. 290,544, dated December 18, 1883.

Application filed September 4, 1883. (No model.)

To all whom it may concern:

Be it known that I, JOSEPH P. DION, of Biddeford, county of York, Maine, have invented a new and Improved Heel-Burnisher and Edge-5 Setter, of which the following is a full, clear, and exact description.

The object of the invention is to improve burnishing-tools and edge-setters, as herein-after described, and pointed out in the claims.

10 Reference is to be had to the accompanying drawings, forming a part of this specification, in which similar letters of reference indicate corresponding parts in all the figures.

Figure 1 is partly a plan view and partly 15 a horizontal section of my improved burnisher and edge-setter. Fig. 2 is a sectional elevation, and Fig. 3 is a face view, of the burnisher.

I arrange a mandrel, *a*, of suitable size and length in bearings *b c* of a suitable frame, and 20 apply a chuck, *d*, to one end, carrying an edge-setter, *e*, said edge-setter being secured in said chuck by a set-screw, *f*, enabling the edge-setter to be shifted out or in, according to the length the head of the edge-setter is required 25 to project from the end of the mandrel, which varies with the thickness of the edge of the sole to be finished by the edge-setter. The chuck is secured to the mandrel by the set-screw *g*, to allow it to be taken off when required. To the other end of the mandrel I apply a disk, *h*, having groove *i* in the side eccentric to the axis of the shaft, for a means of 30 imparting a rising-and-falling motion to the staff of the burnishing-tool *j*, said staff consisting of the bar *k*, pivoted to the machine-frame at *l*, and the bar *m*, confined to and sliding along bar *k* in clips *n*, the bar *k* having a stud-pin, *o*, working in the eccentric groove *i* of the disk *n*. Between the clips *n* of bar *k* a 35 coiled spring, *p*, is arranged around bar *m*, the front end of the spring being connected to bar *m*, and the back end resting against the clip *n*.

The burnisher consists of the convex and 40 obliquely-ribbed face *q* of the head *j* of the bar

m, with a flange, *s*, attached to one side for a gage to the bottom of the heel to control the action of the face *q*.

I may employ a crank-pin in the side of the disk *h*, with suitable connection to the bar *k*, 50 instead of having the pin on the bar and the groove in the disk.

It will be seen that by the contrivance of the staff in two parts, so that the burnisher may have back motion against the spring when the 55 shoe is pressed against it, and is passed up to the work by the yielding force of the spring, the action of the burnisher will be very smooth and easy on the leather, and the effect much better than that of the more positive, and consequently more harsh, contrivances.

A stand may be employed in front of the burnisher to rest the shoe on while holding it on the burnisher, if desired.

The mandrel is provided with a suitable 65 driving-pulley, *t*, and the burnisher-staff is enclosed in a chamber, *u*, of the frame to conceal it and protect it.

The burnisher is attached to the end of bar *m*, and secured by a set-screw, *v*. 70

Having thus described my invention, I claim as new and desire to secure by Letters Patent—

1. The rotary mandrel *a*, carrying the edge-setter *e* at one end and the eccentrically-grooved disk *h i* at the other, in combination 75 with the burnisher-staff having a stud-pin, *o*, whereby said mandrel may operate the edge-setter and burnisher simultaneously.

2. A burnisher-staff consisting of a pivoted bar, *k*, having the clips *n n*, and having a stud-pin, *o*, adapted to work in the cam-slot of a rotary disk, the slide-bar *m*, carrying a burnisher at the lower end, and the spiral spring *p*, all constructed and arranged substantially as shown and described. 80

JOSEPH P. DION.
